DESIGN FOR A DISPLAY STAND

Alice Campbell, New York, N. Y.

Application May 13, 1937, Serial No. 69,335

Term of patent 3½ years

To all whom it may concern:

Be it known that I, Alice Campbell, a citizen of the United States, residing in New York city, county and State of New York, have invented a new, original, and ornamental Design for a Display Stand, of which the following is a specification, reference being had to the accompanying drawing, forming part thereof, and in which the figure is a perspective view of a display stand showing my new design.

I claim:

The ornamental design for a display stand as shown.

ALICE CAMPBELL.
